UNITED STATES PATENT OFFICE.

VIETTS L. RICE, OF NEW YORK, N. Y.

PULVERIZING-MILL.

SPECIFICATION forming part of Letters Patent No. 430,884, dated June 24, 1890.

Application filed March 19, 1890. Serial No. 344,490. (No model.)

To all whom it may concern:

Be it known that I, VIETTS L. RICE, of New York, in the county and State of New York, have invented a certain new and useful Improvement in Pulverizing-Mills, of which the following is a specification.

I will describe a mill embodying my improvement, and then point out the novel features in the claims.

10 In the accompanying drawings, Figure 1 is a vertical section of a mill embodying my improvement. Fig. 2 is a horizontal section taken at the plane of the dotted line $\alpha\alpha$, Fig. 1. Fig. 3 is a horizontal section on the line 15 $\alpha\alpha$, Fig. 1, looking upward.

Similar letters of reference designate corresponding parts in all the figures.

A designates a chamber, here shown as made in the form of a pan. It may be made 20 of any suitable material—as, for instance, of iron. In it is a ring B, which, as here shown, is set into the recess formed in the inner side of the chamber A. This ring forms one of the grinding or pulverizing surfaces, and it 25 may be made of any desirable material—as, for instance, of steel.

C designates a number of rolls arranged to travel around the interior of the ring B. As this ring is in effect a part of the chamber, 30 the rolls may be regarded as traveling around the inner surface of the chamber. There are in the present instance three of these rolls C, and they are affixed to upright shafts D, which are journaled so as to be free to rotate 35 within journal-boxes E, that are arranged in a head F. The head F is of small diameter as compared with the diameter of the chamber A, so that the rolls have to swing outwardly into positions which cause their shafts D to 40 diverge from each other in order to contact with the ring B. The journal-boxes E are provided with trunnions or journals e, which fit in recesses or bearings in the head F in such manner as to allow of the swinging of 45 the rolls C and shafts D outward. The head F is secured to a main shaft G, which is supported in a frame H. This frame H may be made of any suitable material, and consists of a head h and a number of converging 50 standards h' , which are fastened at the upper end to the head and at the lower end rest upon any suitable support. The head h has

a central hub h^2 , and in this is fitted a vertically-adjustable bearing-sleeve I. Internally this sleeve tapers downwardly and within it 55 receives a downwardly-tapering portion of the main shaft G. The main shaft is supported vertically by having affixed to its upper end a driving-pulley I', which has a downwardly-extended portion fitting upon the top 60 of the hub h^2 on the head h of the frame H.

The head F is secured to the lower end of the main shaft G. Hence when the main shaft is rotated the shafts D and rolls C will be revolved around the axis of the main 65 shaft. Centrifugal force generated by this revolution of the rolls and their shafts will cause the rolls to swing outwardly into contact in a surface of the ring B. The friction which will be generated at the surface of the 70 rolls in their rotation will cause them to rotate on their own axes as they are revolved around the chamber. When the rolls are at rest, they will fall away from the wall of the chamber, allowing material to be placed between them and the wall. As soon as looseness occurs through wear between the main shaft G and sleeve I the sleeve may be moved upward to compensate for this wear. I have shown a lever J fulcrumed between its ends 80 in the hub of the head h of the frame H and having a toothed inner end engaging with circumferential grooves and ribs in the sleeve, and this serves as a convenient means for adjusting the sleeve and retaining it in position. Should there be wear on one side of the sleeve more than another, it may be removed, partially rotated, and reinserted, and to enable it to remain in any position into which it may be adjusted I provide it and 85 the hub with a tongue-and-grooved connection. As here shown, equidistantly-arranged tongues i extend from the exterior of the sleeve I into grooves formed in the interior of the hub. The inner surface of the ring B 90 is shown as vertically disposed, and when it is so disposed the rolls will taper downwardly, so that the operating portions of their surfaces will be substantially parallel with the interior of the ring. Above the chamber A, I 95 have shown a circular screen K. It may be mounted directly upon the upper edge of the chamber and constructed to have a slight upward taper. It may be made of any suitable

100

perforated or reticulated material. Its upper edge may be supported from the standards *h'*. Preferably an annular plate *L* will be used above it, and when used will be supported by the standards and connected to the upper edge of the shell, so as to extend inwardly above the latter.

M designates a shell extending around the chamber *A* and having a section which extends around the screen *K*. The space between the screen and upper section of the shell *M* communicates with the space between the exterior of the chamber and the lower section of the shell *M*, and the latter at the lower end is open to a hopper *N*, which is arranged below the chamber and shell. It is intended that material when pulverized to the proper degree of fineness shall escape through the screen and be discharged into the hopper. I have shown one of the shafts *D* as provided with a spiral flange *d*. As this shaft rotates, the spiral flange will lift up the pulverized material and cause it to be distributed well over the surface of the screen as it flies outward against the latter.

N' is a conveyer for removing the pulverized material from the hopper *N*, and *N²* is a chute through which material is fed to the apparatus.

30 What I claim as my invention, and desire to secure by Letters Patent, is—

1. In a pulverizing-mill, the combination of a chamber for receiving material to be pulverized, a main shaft, a number of rolls, shafts upon which these rolls are mounted, a head connected to the main shaft, and oscillating journal-bearings having such relation to the main shaft that when the rolls are at rest said rolls will fall away from the wall of the chamber, substantially as specified.

2. In a pulverizing-mill, the combination of a chamber for receiving material to be pulverized, a number of rolls arranged to travel around the interior of the same, shafts connected with the rolls, and a main shaft serving to revolve the roll-shafts, but connected loosely therewith, so as to allow the roll-shafts to rotate on their own axes independently, one of said roll-shafts having a spiral flange, substantially as specified.

3. In a pulverizing-mill, the combination of a chamber for receiving material to be pulverized, three rolls arranged to travel around the interior of the same, three shafts connected with the rolls and arranged to be equidistant at their upper ends, a main shaft serving to revolve the roll-shafts, but connected loosely therewith, so as to allow the roll-shafts to rotate on their own axes independently, and a 60 longitudinally - adjustable bearing for the main shaft, substantially as specified.

4. In a pulverizing-mill, the combination of a chamber for receiving material to be pulverized, a downwardly-tapering roll arranged to travel around the interior of the same and having the outer portion of its surface substantially parallel with the vertical wall of the

chamber, a shaft connected with the roll, a head in which said shaft is journaled so as to be capable of rotation therein, and a main shaft connected to said head and serving to revolve the roll, substantially as specified.

5. In a pulverizing-mill, the combination of a chamber for receiving material to be pulverized, a roll arranged to travel around the interior of the same, a shaft connected with the roll, a main shaft, an adjustable bearing-sleeve for the main shaft, having means, substantially as specified, for retaining it as adjusted, a head secured to the main shaft, and a journal-box receiving the roll-shaft and having an oscillating connection with the said head, substantially as specified.

6. In a pulverizing-mill, the combination of a chamber for receiving material to be pulverized, a roll arranged to travel around the interior of the same, a shaft connected with the roll and provided with a spiral flange, and a main shaft revolving the roll-shaft, substantially as specified.

7. In a pulverizing-mill, the combination of a chamber for receiving material to be pulverized, a roll arranged to travel around the interior of the same, a shaft connected with the roll, a main shaft having a downwardly-tapering portion, a frame or standard through which said main shaft passes, a pulley attached to the upper end of the said main shaft and having a bearing upon the said frame or standard for the purpose of sustaining the main shaft vertically, a sleeve having an upwardly-flaring interior surface fitting the downwardly-tapering portion of the main shaft and an exterior fitting a cavity or opening in the said frame or standard, and a lever engaging with the sleeve for adjusting it longitudinally, substantially as specified.

8. In a pulverizing-mill, the combination of a chamber for receiving material to be pulverized, a roll arranged to travel around the interior of the same, a shaft connected with the roll, a main shaft having a downwardly-tapering portion, a frame or standard through which said main shaft passes, a pulley attached to the upper end of said main shaft and having a bearing upon the said frame or standard for the purpose of sustaining the main shaft vertically, and a sleeve tapering internally to fit the tapering portion of the main shaft and having a tongue-and-grooved connection with a cavity in the said frame or standard, whereby said sleeve may be removed, and after being partially rotated may be reinserted to present its surfaces more advantageously for wear, substantially as specified.

9. In a pulverizing-mill, the combination of a chamber for receiving material to be pulverized, a roll arranged to travel around the interior of the same, a perforated or reticulated screen rising from the said chamber, a shell surrounding the screen-chamber, and a hopper arranged beneath the chamber and having its upper portion extended beneath

the space which is between the chamber and the said shell, and a spiral flange carried by the roll to carry material to the screen, substantially as specified.

5 10. In a pulverizing-mill, the combination of a chamber for receiving material to be pulverized, a main shaft, a number of taper rolls, shafts upon which these rolls are mounted, a head connected to the main shaft,

and oscillating journal-bearings for the roll-shafts located so close to the main shaft that when the rolls are at rest said rolls will fall away from the wall of the chamber, substantially as specified.
